UNITED STATES PATENT OFFICE.

A. P. SMITH, OF STERLING, ILLINOIS.

IMPROVEMENT IN WINDOW-BLINDS.

Specification forming part of Letters Patent No. **56,282**, dated July 10, 1866.

To all whom it may concern:

Be it known that I, A. P. SMITH, of Sterling, Whiteside county, State of Illinois, have invented a new and useful Improvement in Window-Blinds; and I do hereby declare that the following is a full, clear, and exact description thereof, which will enable others skilled in the art to make and use the same, reference being had to the accompanying drawings, forming part of this specification.

The present invention relates to that class of window-blinds in which the slats composing the same are hung by suitable tenons at each end, so as to turn within the side pieces of the blind-frame, and the several slats of each section connected together with a rod, by the moving of which up and down the slats were either opened from or closed upon each other; and it consists in a novel attachment to the said slat-rod, whereby the slats can be, when opened or closed more or less, secured and held in such position, the slats, when closed upon each other, and the blinds shut by means of this novel attachment, being impossible to move from the outside, thus becoming, in a measure, burglar-proof.

In accompanying plate of drawings my improvement in window-blinds is illustrated, Figure 1 being a front view of a blind with it applied thereto, and Fig. 2 a transverse vertical section taken in the plane of the line *x x*, Fig. 1.

Similar letters of reference indicate like parts.

A in the drawings represents a window-blind having a series of slats, B B, which, at each end, are hung by tenons in the ordinary manner within the side pieces, C C, of the blind-frame, these slats being connected by a common center vertical rod, D, in such a manner

that by the moving of it either up or down they will be either opened or closed, as the case may be. In the lower end of the rod D is hung one end of a lever frame or catch, E, the other end of which passes in and between the notched or rack bar G, secured at each end by screws, or in any other proper manner, to the lower rail, H, of the blind-frame, and has its lower cross-bar, I, engaged with the notches of such bar G, and so held by means of a bent spring, J, properly arranged therefor, and secured at one end to the blind-rail, which spring acts through a plate, K, interposed between it and the said lever-frame E.

L is a handle or thumb-piece formed upon the lower end of lever-frame E, by the depressing and bearing against of which with the thumb or finger of the hand the lever-frame E is disengaged from the notch-bar, thus leaving the slat-rod, to which it is hung, free to be either moved up or down, according as it may be desired to either open from or close the blind-slats upon each other, the slats being held in any position to which they may be brought and within the limit of their swing upon the blind-frame by the interlocking of the lever-frame E with the rack or notched bar G, as is obvious without further explanation, the advantages of which are manifest.

I claim as new and desire to secure by Letters Patent—

Connecting the slat-rod D to the blind-frame through a catch and rack or notched bar, when all are arranged together and so as to operate substantially in the manner described, and for the purpose specified.

A. P. SMITH.
